DESIGN FOR A FOLDING CURLER COMB

Eleanor S. Berliner, Westchester County, N. Y.,
assignor to Injection Moulding Corp., New
York, N. Y., a corporation of New York

Application August 17, 1938, Serial No. 79,410

Term of patent 7 years

To all whom it may concern:

Be it known that I, Eleanor S. Berliner, a citizen of the United States, with residence in the county of Westchester, State of New York, and Post Office address at No. 1 Harrison Street, New Rochelle, New York, have invented a new, original, and ornamental Design for a Folding Curler Comb, of which the following is a specification, reference being had to the accompanying drawing, forming part thereof, in which:

Figure 1 is a side elevational view of a folding curler comb showing my new design in unfolded position;

Figure 2 is a side elevational view thereof in folded position; and

Figure 3 is a cross-sectional view looking in the direction of the arrows on line 3—3 of Figure 1.

The essential features of my design reside in the specific configuration, contour and proportions of the curler in combination with the comb, as shown and described.

The other side of the folding curler comb is identical to the side shown in the drawing.

I claim:

The ornamental design for a folding curler comb, as shown and described.

ELEANOR S. BERLINER.
